(57) **CLAIM**

The ornamental design for an integrated mounted frame for an unmanned vehicle, as shown and described.

DESCRIPTION

FIG. 1 is a first front perspective view of an integrated mounted frame for an unmanned vehicle, showing our new design;

FIG. 2 is a second front perspective view of an integrated mounted frame for an unmanned vehicle, showing our new design;

FIG. 3 is a third front perspective view of an integrated mounted frame for an unmanned vehicle, showing our new design;

FIG. 4 is a front elevation view of the integrated mounted frame for an unmanned vehicle shown in FIG. 1;

FIG. 5 is a rear elevation view of the integrated mounted frame for an unmanned vehicle shown in FIG. 1;

FIG. 6 is a left side elevation view of the integrated mounted frame for an unmanned vehicle shown in FIG. 1;

FIG. 7 is a right side elevation view of the integrated mounted frame for an unmanned vehicle shown in FIG. 1;

FIG. 8 is a top plan view of the integrated mounted frame for an unmanned vehicle shown in FIG. 1; and,

FIG. 9 is a bottom plan view of the integrated mounted frame for an unmanned vehicle shown in FIG. 1.

The broken lines represent portions of the integrated mounted frame for an unmanned vehicle and form no part of the claimed design.

1 Claim, 7 Drawing Sheets
